UNITED STATES PATENT OFFICE.

LEON LETALLE, OF BEAUVAIS, FRANCE.

LOOM FOR WEAVING CHENILLE WEBS.

SPECIFICATION forming part of Letters Patent No. 473,260, dated April 19, 1892.

Application filed March 20, 1891. Serial No. 385,933. (No model.) Patented in France May 6, 1879, No. 130,518; in England January 2, 1891, No. 75; in Austria-Hungary February 7, 1891, No. 7,592 and No. 22,875, and in Germany February 24, 1891, No. 58,288.

To all whom it may concern:

Be it known that I, LEON LETALLE, a citizen of the French Republic, residing at Beauvais, in the Department of the Oise and Republic of France, have invented an Improvement in Looms for Weaving Chenille Intended for the Weaving of Carpets and other Chenille Fabrics, (for which Letters Patent were granted in France May 6, 1879, No. 130,518; 5 in England January 2, 1891, No. 75; in Austria-Hungary February 7, 1891, No. 7,592 and No. 22,875, and in Germany February 24, 1891, No. 58,288,) of which the following is a specification.

15 The manufacture of long-pile carpets with chenille weft is effected by ordinary means as follows: Each weft-thread of chenille is made beforehand and is composed of as many points of different colors as required by the 20 design or pattern. To obtain this result a fabric is woven composed of warp-threads set wide apart, and these threads serve to bind the woolen weft-threads, which are each of the color required by the pattern. After the 25 weaving this fabric is divided into strips or bands by cutting the weft-threads along the spaces between the warp-threads. Each of these cut threads of chenille will result in a part or point of the design of the carpet, and 30 the entire strip or band will serve as weft for its composition. The order in which these wefts of chenille are placed in the weaving of the carpet determines the arrangement of the pattern.

35 Weaving long-pile fabrics by hand occupies much time by reason of the large number of shuttles to be worked.

The loom forming the subject of this invention has for its object the mechanical weaving 40 of the fabric for the chenille wefts by dispensing with the shuttles and replacing them by a single pincher or nipper having an analogous to-and-fro motion, and which at each movement seizes and carries a weft-thread 45 through the shed. Therefore to obtain the variety of color given by the several shuttles it is only necessary to present a different thread to the nipper at each of its movements, this result being produced by the distributor

with keyboard placed on the left-hand end of 50 the loom:

My invention is illustrated in the accompanying drawings, in which—

Figure 1 shows in detail the chenille web, which is cut apart to produce weft-threads. 55 Fig. 2 is a side view of a loom having applied thereto the distributor embodying my invention. Fig. 3 shows one side of the loom, the distributor and manner of fixing it thereto, and the box containing the bobbins of wool. 60 Figs. 4 and 5 are enlarged detail views of parts of this distributor. Fig. 6 is a side view of the nipper. Fig. 6^a is an end view of same. Fig. 7 is a plan view of the nipper and shears. Fig. 8 is a side view of the shears, 65 showing the manner of attaching them to the batten-arm X. Fig. 9 is a front view of the entire loom. Fig. 10 is a front view of the distributor, showing the working connections to the keyboard. Fig. 11 is a sectional plan 70 view taken on the line X Y of Fig. 10. Fig. 12 is a sectional view taken on the line n n' of Fig. 10, and it also shows the box containing the bobbins a'. Figs. 13, 14, and 15 are details of the various parts of the distributor. 75 Fig. 9 is a general view of the loom and distributor and a good idea of the arrangement and relation of the various parts will be obtained from an inspection of it.

D' is the distributor.

Y is the stationary frame of the loom.

X is the batten-frame, which carries the guide G' for the needle N' and needle-bar T. H is a support for the needle, fixed to the loom-frame by a brace b'.

The batten is operated by the crank-shaft z, connections z' z', and bar b², which is fixed to the batten-frame X X. The needle N' is reciprocated by the eccentric V² and spring R² through the rods r¹ r² r³. A latch X² is 90 provided to hold the needle N' stationary in the support H while the batten X' is making its beat. This latch is operated by the small eccentric v², which is placed upon the same shaft with the large eccentric V². A revolution of the two eccentrics will operate as follows: The small eccentric v² will depress the rod r⁵, which will draw down the rod r⁴ and 95

lift the latch X^2 , which will be returned to its position by the spring s^2 . At the same time the revolution of the eccentric V^2 will throw back the rod r' , which will pull the rod r^2 , which will draw back the rod r^3 , which in turn will throw the needle-bar T and needle N' . This movement will alternate with the beat of the batten, as in ordinary looms.

The construction and operation of the distributor and its relation to the parts of the loom will be now described.

An inspection of Figs. 2, 3, and 9 will show that the distributor is attached to the stationary frame Y of the loom by a bracket or casting Z' , upon which is also carried the keyboard K' .

The various detail parts of the distributor assembled in operative position and their relation to each other will be more clearly seen by reference to Figs. 10 and 15 and also Figs. 4 and 5. As seen in Fig. 10, Z is a circular casting bored to receive the bearings of the pivots 1 2 3 4 5 6, &c. Each of these pivots has a sector C , of thin sheet-iron, at one end and at the other a grooved pulley c , Fig. 3. This pulley c , Fig. 15, is not entirely circular, but is of semi-circumferential form, so as to occupy less space and to permit the superposition of a greater number of them. Each of the pulleys c is connected by a cord d to a bell-crank lever E , forming a key, as in a piano. The cord is fixed to the pulley c , but extends beyond to an anchorage e' . An adjusting-spring D , interposed in the length of the cord, keeps the key in its place. Each of the cords d passes over one of the return-pulleys e . When the operator desires to bring a color to the point O , he presses upon the corresponding key, (which custom teaches him quickly.) The key E takes the position Fig. 14. The tension which it operates upon the cord d causes the half-pulley with groove c to pivot. This pivots the axle upon which one of the sleeves is fixed. This lowers the sector C , and it takes the position represented in Fig. 10. The tube B , which terminates it, is then facing the nipper of the loom and has carried the desired thread there. On releasing the key the spring D brings back the pulley c , the sector C , and the lever E , and the key resumes its normal position. A stop-rod w , Figs. 10 and 14, limits the position of the bent lever E , which, being always acted upon by the spring, constantly rests upon it. The workman thus changes color by working this or that key, which brings the tube carrying the thread of wool to the center of the apparatus.

At section, Fig. 12, it will be seen that each of the sectors, being independent, may be displaced with facility. Then being set upon axles of different lengths permits them, in superposing, to slide the one behind the other. Their sector shape permits them to carry the tube to the center without the other tubes being an obstacle.

The lay or batten X is furnished with a toothed guide G' to receive and guide a nip-

per N' , which is constructed as follows: Two steel jaws ff' , Figs. 6 and 7, are fixed upon a metal part or head F . These jaws are of 70 spring metal and tend to close upon each other with considerable force. A cam G , having a finger g attached to it by which it is operated, is pivoted between the jaws ff' . The cam G is turned at one end of the throw of 75 the needle N' by the finger g coming in contact with the finger v on the batten and at its opposite end of the throw by the finger t , also upon the batten.

The shears which cut the thread off before 80 it is tightened up by the batten are constructed of an arm or blade L , fixed to the batten-frame X , and a movable arm or blade M , pivoted upon the fixed arm L . A spring N keeps the arms normally apart. Mounted upon the 85 arm M is a roller m , which at each stroke of the batten comes in contact with the roller Q upon the loom-frame Y , contact with which will force the arm M down upon the arm L and cut the weft-thread. The shears are 90 duplicated at the other end of the batten, there being this difference, that the shears at the right do not cut, but merely take the weft-thread from the nipper and hold it taut, so that it may be driven into place by the batten. 95

The working of this loom is exceedingly simple. When the operator has chosen the thread which is required, he works the corresponding key, which brings the tube B to the center O at the moment that the batten is at 100 its backward position. At this moment the eccentric V^2 actuates the nipper, as already described, which comes as far as onto the tube B , and is then permitted to close by the finger g coming into contact with the finger v , 105 and thereby turning the cam G . At this moment the eccentric V^2 has made a half-revolution, and no longer acting on the connecting-rods the spring R^2 brings the nipper backward, and at the same time this latter 110 draws the woolen thread through the warp. The batten or lay X then makes its forward movement to beat up this weft of wool. Before reaching the end of its journey the rollers m of the shears carried by the batten strike 115 against the rollers Q and the shears close. Those on the left, which are cutting, produce the section of the woolen thread, which thus finds itself separated from the tube B , but nevertheless held by the shears, which nip 120 at the same time that they cut. Those on the right, which are simply nipping, hold the woolen thread. Just before ending its journey the batten brings the latch s against the striking pieces or stops R , which release the shears, 125 permitting them to open, thus releasing the woolen thread and permitting the batten to tighten it up. At the same time the rod t , which is fixed to the batten, acts on the small cam G , which it causes to pivot in order to 130 open the nipper. The batten then retires to permit the nipper to return and seize another thread.

Having described my invention, what I

- claim, and desire to secure by Letters Patent, is—
1. The combination, in a loom for weaving webs for making chenille, of a distributor, a keyboard operating it to center the weft-threads at a point common to all and a needle catching the thread presented at the common center, and means, substantially as described, for drawing the needle and thread through the shed. 10
  2. In a loom for weaving webs for making chenille, a distributor having a plurality of pivoted weft-carrying sectors centering at a point common to all, a keyboard having a plurality of keys, and connections between each key and one of the sectors, whereby they are operated. 15
  3. In a loom for weaving webs for making chenille, a distributor comprising a support, a keyboard, weft-carrying sectors independently pivoted to the support and centering the weft-threads at a point common to all, independent actuating connections between each of the sectors and a key of the keyboard, and means for drawing the weft-threads into position between the warp-threads. 20 25
  4. In a loom for weaving webs for making chenille, a distributor comprising a support and keyboard, weft-carrying movable sectors independently pivoted to the support, and a suitable nipper for seizing a weft-thread upon the depression of one of the keys of the board, and means, substantially as described, for drawing said nipper through the warp-threads, substantially as described. 30 35
  5. In a loom for weaving webs for making chenille, a distributor comprising a circular support and keyboard, movable weft-carrying sectors independently pivoted to the support, a suitable nipper for seizing a weft-thread upon the depression of one of the keys of the board, means, substantially as described, for drawing said nipper through the warp-threads, and shears for cutting each thread after it has been laid, substantially as described. 40 45
